UNITED STATES PATENT OFFICE

HERMANN FISCHER, OF BERLIN-NEUKOLLN, GERMANY, ASSIGNOR, BY MESNE ASSIGNMENTS, TO PAUL REINHARDT, OF BERLIN, GERMANY

SPARKING PLUG

Application filed May 28, 1928, Serial No. 281,239, and in Germany June 4, 1927.

My invention relates to sparking plugs and it is an object of my invention to provide a plug in which the good insulating and other properties of certain materials are fully utilized and the influence of their less desirable properties is eliminated.

To this end, I provide resilient supporting means for supporting such insulating materials.

10 Failure of sparking plugs is a frequent cause of trouble in the operation of internal combustion engines, and of grave accidents, as in airplanes. The excellent properties of quartz glass as an insulating material are 15 fully appreciated and it has often been attempted to equip sparking plugs with quartz insulators, but heretofore such insulators were not satisfactory on account of their short life.

20 This drawback is overcome in my invention in which a quartz tube surrounding the inner electrode of the sparking plug is provided so as to be absolutely tight under maximum compression and explosion pressures, 25 but is supported by resilient means.

I shall describe a sparking plug having an insulating tube of quartz glass, but it is understood that I am not limited to this material as not only quartz glass but quartz and 30 all other suitable materials, as ceramic materials, may be used. Preferably the softening temperature of the material is beyond the average temperature in the combustion chamber of the cylinder.

35 In the accompanying drawing I have illustrated an axial section of a sparking plug according to my invention, on an enlarged scale.

40 Referring now to the drawing, *a* is the body or outer electrode of the plug, *b* is a sleeve screwed into the body and surrounding the inner electrode or ignition pin *c* at some clearance, *d* is a tapered tube of suitable insulating material, quartz glass in the present instance, *e* is an annular clearance between the inner wall of the tube *d* and the electrode *c*, *f* is a sheath of some layers of mica or other silicate which is wound on the electrode *c*, *g'* is a flange formed on the inner end *g* of the electrode, *h* are washers of

silicate inserted between the flange *g'* and the inner end of the electrode insulating tube *d*, *k* are washers of silicate on the outer end of the tube *d*, *l* is a washer of aluminium or the like placed on the washers *k*, *m* is a ring 55 of resilient material, and *n* is a nut on a threaded portion *o* of the electrode *c* which exerts thrust on the ring *m* and holds the tube *d* under the resilient pressure of the ring *m*.

60 *p* are washers of mica or other silicate which are placed over the tube *d* in a cavity of the sleeve *b* and are bored tapering so as to fit the taper of the tube *d*, *q* is a threaded sleeve in the cavity of the sleeve *b*, *r* is a 65 shoulder at the end of the cavity on which the set of washers *p* are supported, *s* is a tube of insulating material which is seated on the sleeve *q*, and *t* is a nut on the thread of the electrode which exerts thrust on the 70 tube *s*.

The plug is assembled as follows:

The silicate rings *h* are placed on the flange *g'*, the sheath *d* is wound tightly about the inner electrode *c*, the tube *d* is placed on 75 the washers *h* with its end *i* which is ground exactly square, the washers *k* are placed on the outer end of the tube *d*, the aluminium washer *l* is placed on the washers *k*, the ring *m* is inserted between the washer *l* and the 80 nut *n*, and the nut is set. The assembled inner electrode unit is then inserted in the sleeve *b*, the washers *p* are placed on the tube *d* in the cavity of the sleeve, the sleeve *q* is inserted, the tube *s* is placed on the sleeve 85 *q* and the nut is set.

The annular clearance *e* between the electrode *c* and the tube *d* is important as it prevents short-circuiting of the electrode *c* past the mica washers *b* to the body of the plug 90 when the tube *d* should become cracked, and carbon particles should penetrate into the clearance *e*. A further protection is afforded by the sheath *f*. Gas or a vacuum may be present in the clearance *e*.

95 The washers *h* and *k* constitute resilient cushions which, together with the ring *m*, absorb the thrust of the nut *n*, and prevent damage to the tube *d*. Besides, they form tight packings. The washers *p* serve the 100

same objects, forming a sort of resilient bearing for the tube *d*. Resilient support of the tube *d* is, as mentioned, particularly important when the tube is of quartz or quartz glass.

The tube *s* is a protecting casing and may be of quartz, ceramic material, silicates, as mica, and the like, and resilient, if desired.

Preferably, the material of the tube *d* and 10 of the washers *p* which surround the tube, should have equal, or substantially equal, expansion coefficients, a condition which is fulfilled in the case of quartz and mica.

I claim:

15 1. A sparking plug comprising a body forming an outer electrode, an inner electrode arranged within the body, an inner insulating tube arranged in spaced surrounding relation about the inner electrode and 20 having a conical outer surface, an outer insulating tube having a conical inner surface, means on the body for forcibly inserting the outer insulating tube into the body, and means on the inner electrode to draw firmly 25 the inner insulating tube into the outer insulating tube.

2. A sparking plug comprising a body forming an outer electrode, an inner electrode arranged within the body, an inner insulating tube arranged in spaced surrounding 30 relation about the inner electrode and having a conical outer surface, an outer insulating tube having a conical inner surface and composed of rings of mica, means on the 35 body for forcibly inserting the outer insulating tube into the body and between the body and the inner insulating tube and means on the inner electrode to draw firmly the inner insulating tube into the outer insulating tube.

40 3. A sparking plug comprising a sectional body forming an outer electrode, an inner electrode arranged within the body, an inner insulating tube arranged in spaced surrounding relation about the inner electrode, 45 an outer insulating tube surrounding the inner insulating tube, means for forcibly inserting the outer insulating tube into the body, a collar on the inner end of the inner electrode, a layer of mica wrapped about the 50 inner electrode adjacent the flange, mica layers on said collar for supporting the inner insulating tube, clamping means adjustably mounted on the outer end of the inner electrode, and a resilient ring, an aluminium 55 washer and mica layers successively interposed between the clamping means and the outer end of the inner insulating tube.

In testimony whereof I affix my signature.
HERMANN FISCHER.
